DESIGN FOR A SILVERWARE POLISHING
STAND

Amanda S. Seager, Glendale, Calif.

Application November 22, 1948, Serial No. 149,749

Term of patent 14 years

(Cl. D9—2)

To all whom it may concern:

Be it known that I, Amanda S. Seager, a citizen of the United States, residing at Glendale, in the county of Los Angeles and State of California, have invented a new, original, and ornamental Design for a Silverware Polishing Stand, of which the following is a specification, reference being had to the accompanying drawing, forming part thereof.

Fig. 1 of the drawing is a plan view of a silverware polishing stand, showing my new design;

Fig. 2 is a side elevational view thereof; and

Fig. 3 is an end view thereof.

I claim:

The ornamental design for a silverware polishing stand, as shown.

AMANDA S. SEAGER.
